UNITED STATES PATENT OFFICE.

MICHAEL POWERS, OF BOSTON, MASSACHUSETTS.

SCAFFOLD HANGER.

Application filed December 31, 1926. Serial No. 158,230.

This invention relates to movable scaffolds and one object of the invention is to provide an improved scaffold hanger for that type of scaffold that may be used singly or 5 in multiple, and having, among others, the novel features and advantages hereinafter described.

In the drawings of one embodiment of my 10 invention illustrated and described herein, Fig. 1 is a side elevation of one hanger with the floor planks, the roof and certain other parts of the scaffold thereon in section;

Fig. 2, an end elevation of two hangers 15 and the scaffold floor and roof positioned for use, partly broken away;

Fig. 3, a vertical detail from the right, partly in section, on the line 3—3, Fig. 1, the gears being shown in elevation;

20 Fig. 4, a vertical detail partly in section on the line 4—4, Fig. 1; and

Fig. 5, a side elevation of two of the scaffold hangers, in tandem arrangement with a modified form of supplementary floor adjusting means, the roofs and floors shown in 25 section.

Referring first to Fig. 1, my novel scaffold hanger comprises two raising and lowering units or devices which may be referred to 30 individually as *a*, *b*, substantially identical in construction, so that a detailed description of one of them will be sufficient.

Each device comprises, preferably, Figs. 1, 2, a shaft 1 carrying at its outer end a 35 bearing member 2 therefor, which may be circular, from which depends a permanent floor support as a cable 3, stationary thereon and secured at its lower end to one or more, herein two, floor supporting bars 4, as back 40 to back positioned angle irons, which irons carry the planks 5 of the scaffold.

Each shaft 1, Figs. 1, 2, also carries near 45 its outer end a roof and rail supporting plate or other suitable member 6, which supports a bar 7 as a U-bar, the ends of which, Fig. 2, may be conveniently turned up to hold in position the planks 8 forming the roof. Each shaft 1 also carries, preferably near its end, the pulley or drum 9, on which is 50 wound one end of a supporting cable 11, the opposite end of which is secured to the outrigger 12 or other suitable support which may be an I beam extended outwardly from the building 10, the cable 11 being used 55 to raise or lower the scaffold to and from the

beam as desired, by mechanism to be described.

Each shaft 1 also carries, preferably at one end, a supplemental floor adjusting pulley 13 which may be separate from the pulley 9 or obviously the pulley 9 may be provided with a second groove to take the place of the pulley 13, for carrying a cable 14 secured to the floor bars 4 at its lower end, while its upper end is secured to the pulley 13, for providing a supplemental raising and lowering adjustment of the bars 4 and their platform planks 5, as will be more specifically described.

For operating the shaft 1, Fig. 1, to raise or lower the scaffold as a whole, each shaft is connected to a, preferably, common gear 16 in mesh with a pinion 17 journaled in a frame like member 18 carried by the shaft 1. This member 18, Figs. 1, 2, 3, also carries opposed tie bars 19 in which is journaled the worm 20 also in mesh with the pinion 17, the worm being operated, Fig. 3, by the handle 21 which may be removable and for use on either end of the worm shaft. 70 The frame 18, Fig. 1, is positioned between and secured to the U-shaped anchoring bracket 22, thereby stabilizing the frame and its gears, and preventing any movement of the frame relative to the shaft 1. 75

One other additional form of control is here shown in Fig. 1, and also in Fig. 4, in dotted lines, where a handle 23 forked at one end 24 to engage the shaft 1 and having a pivoted pawl 25 may be used in case of accident to any of the gears 16, 17 or worm 20, to operate the shaft 1 to raise or lower the scaffold, a dog 26, Figs. 1, 2, on the plate 27, secured to the bar 7, serving to lock the gear 28 on the shaft in desired position. 80 The handle 23 is preferably removable and applied to the shaft 1 only when required. 85

The operation of my novel scaffold support is as follows:

The cables 11 having been made fast to 100 the outrigger 12, the support is lowered by the cables to the ground, the planks 5 placed on the bars 4 and the scaffold raised to a level with the work. As the work proceeds, the scaffold is raised as desired from time to time by means of the handle 21 and gears 16, 17 and worm 20, as described. During this period the supplementary cables 14 are detached from the pulleys 13. When the covering or roof 8 of the scaffold ap- 105 110

proaches closely the outrigger 12, and the limit of travel, the cables 14 are secured to the pulleys 13, by any convenient means, as by inserting the cables through holes in the 5 pulley walls and securing a block on the cable end, and the cables 14 will thus wind up on the pulleys 13 a little faster than cables 11 will wind up on pulleys 9, when the latter are rotated, as the pulleys 13 are 10 larger in diameter than the pulleys 9. Hence, by the time the roof 8 of the scaffold reaches the bar 12, the limit of travel, the floor 5 will have been raised materially relative to the roof 8 so that the workmen can 15 work at a higher level than would otherwise be the case, and obtain longer effective use of the scaffold floor.

Scaffolds of this general type now in use have their raising and lowering devices at 20 the floor level, substantially, thus being near the feet of the workmen, and in the way, and therefore dangerous to their safety; while in my novel construction the raising and lowering devices or controls are well 25 up and out of the way of the workmen, over their heads, so that they cannot trip over them, and the floor space is all available. The controls are carried by the shaft 1 and are simple in construction. Furthermore, 30 the supplementary raising and lowering device permits an adjustment of the scaffold floor that is new and very valuable from the time saving point of view, and that of convenience. Of course the roof 8 may also be 35 used as a floor if desired, by moving the material and tools up there.

In Fig. 5 I have shown a modified form of pulley or drum for the supplementary adjustment.

40 In this case the pulley 9 is provided on its outer face with lugs 30 and the adjusting pulley 13 is provided on its adjacent face with cooperating lugs 31. Between the two pulleys on the shaft 1 is a pulley or 45 clutch releasing spring 32 acting normally to separate the two pulleys. Near the end of the shaft which, in each case, is threaded, there is provided a large nut 33 which, when it is turned up will throw the pulley 13 50 against the pulley 9 causing the lugs 30 thereon to lock with the lugs 31 and, therefore, when the pulley 9 is rotated, thus raise the floor 5 relative to the shaft 1, as already described. Of course unscrewing the nut 33 55 will release the pulley 13 from pulley 9 and permit the cable 14 to unwind and the floor to descend.

60 In this form of construction also the scaffolds are shown in tandem formation, one above the other, as many being used as needed, the second and each subsequent scaffold cable 11 being shown as suspended from a supporting chain 34 made fast to the outrigger 12 and running through the floors of 65 each scaffold to the ground.

In this case too there may be a floor suspending cable 35 from each floor 5 to the anchor chain 34 corresponding to the cable 3 in the construction shown in Fig. 1.

The shaft 1 and its gears are in each case provided as in Fig. 1, and shown in dotted lines in Fig. 5 for convenience. At the end of each shaft 1, or adjacent the pulley 13, Fig. 5, are two collars 36, 37, secured to the shaft, and between them is secured in each case the bar 6, which carries the roof beam 7 and the rail supports or eyes 38 for the rail 39. The bar 6 above the shaft is preferably made in two parts for convenience, the lower end of the upper section being provided with a socket 40 to receive the upper end of the lower section, making the rail support above the shaft 1 removable when desired.

This invention is not restricted to the particular embodiment thereof described and illustrated herein, and I claim:

1. A movable scaffold support comprising a shaft, a pulley thereon with a shaft supporting main cable for attachment to any suitable outrigger, a floor and its support suspended from the shaft, a supplementary floor adjusting pulley on the shaft with a cable secured to the floor and operative with the main cable to effect supplementary floor adjustment and operative control for the shaft of the overhead type.

2. A movable scaffold support comprising a shaft, a pulley thereon with a shaft supporting main cable for attachment to any suitable outrigger, a floor and its support suspended from the shaft, a supplementary floor adjusting pulley on the shaft with a cable secured to the floor and operative with the main cable to effect supplementary floor adjustment, and operative control for the shaft carried by the shaft.

3. A movable scaffold support comprising a shaft, a pulley thereon with a shaft supporting main cable for attachment to any suitable outrigger, a floor and its support suspended from the shaft, a supplementary floor adjusting pulley on the shaft with a cable secured to the floor and operative with the main cable to effect supplementary floor adjustment, and operative control for the shaft carried by the shaft, and comprising a gear thereon, a frame, a pinion thereon, and a worm cooperating with the gear.

4. A movable scaffold support comprising a shaft, a pulley thereon with a shaft supporting main cable for attachment to any suitable outrigger, a floor and its support suspended from the shaft, a supplementary floor adjusting pulley on the shaft with a cable secured to the floor and operative with the main cable to effect supplementary floor adjustment, and operative control for the shaft carried by the shaft and comprising a gear thereon, a frame, a pinion thereon, a worm cooperating with the gear, and a

roof and hand rail support carried by the shaft.

5. A movable scaffold support comprising a shaft, a pulley thereon with a shaft sup-

5 porting main cable for attachment to any suitable outrigger, a floor and its supporting member suspended from the outrigger, means to suspend the floor therefrom, a supplementary floor adjusting pulley on the

10 shaft with a cable secured to the floor, means for locking the last mentioned pulley to the first mentioned pulley to cause it to be operative therewith to effect supplementary floor adjustment, operative control for the shaft

15 carried by the shaft, and emergency control for the shaft cooperating with the first mentioned pulley and the shaft.

6. A movable scaffold support comprising a shaft, a pulley thereon with a shaft sup-

20 porting main cable for attachment to a suitable outrigger, a permanent floor support and floor suspended from the shaft, a supplementary floor adjusting pulley on the shaft larger than the first mentioned pulley

25 and with a cable secured to the floor and operative with the main cable to effect supplementary floor adjustment simultaneously with the main cable adjustment, and operative control for the shafts.

30 7. A movable scaffold construction comprising an outrigger, a plurality of perma-

35 nent scaffold suspending members thereon, a plurality of movable scaffold supports comprising each a shaft, a pulley thereon with a shaft supporting main cable for attachment to any permanent support; a floor and support therefor suspended from the permanent scaffold suspending member, a floor support suspended from the shaft and a supplementary floor adjusting pulley on the

40 shaft with a cable secured to the floor and operative with the main cable to effect floor adjustment simultaneously with the main cable adjustment and operative control for the shaft.

45 8. A movable scaffold support comprising a shaft 1, a pulley 9 thereon with a shaft

50 supporting main cable 11 for attachment to an outrigger; a permanent floor support 3 and floor suspended from the shaft; a supplementary floor adjusting pulley 13 on the shaft, with a cable 14 secured to the floor and having limited cooperating action to adjust the floor 5 relative to the shaft 1 while both are being adjusted relative to the outrigger; and a gear operated control device near the center of the shaft, and a ratchet operated control device near its end.

55 In testimony whereof, I have signed my name to this specification.

MICHAEL POWERS.
